DESIGN FOR A FINGER RING

Morris Kahn, New York, N. Y.

Application November 16, 1938, Serial No. 81,144

Term of patent 14 years

To all whom it may concern:

Be it known that I, Morris Kahn, a citizen of the United States, residing at New York, in the county of New York and State of New York, have invented a new, original, and ornamental Design for a Finger Ring, of which the following is a specification, reference being had to the accompanying drawing, forming part thereof, in which:

Fig. 1 is a fragmentary developed plan view of a ring embodying my new design;

Fig. 2 is a side elevation of the ring taken in the direction of the arrow 2 in Fig. 1;

Fig. 3 is a side elevation of the ring taken in the direction of the arrow 3, in Fig. 1.

The design is formed of a central mounting, comprising a square and compass with the letter G associated therewith, there being a plurality of tools and symbols used as ornamentations arranged in spaced juxtaposition on each side of the central mounting.

I claim:

The ornamental design for a finger ring, as shown and described.

MORRIS KAHN.
